UNITED STATES PATENT OFFICE.

J. FRANKLIN PECK, OF SPRINGFIELD, MASSACHUSETTS.

IMPROVED SPRING BED-BOTTOM.

Specification forming part of Letters Patent No. **90,384**, dated May 25, 1869.

To all whom it may concern:

Be it known that I, J. FRANKLIN PECK, of Springfield, county of Hampden, and State of Massachusetts, have invented new and Improved Methods of Constructing Spring-Beds; and I do hereby declare that the following is a full and exact description thereof, reference being had to the accompanying drawings and letters of reference thereon.

The nature of my invention consists in rendering the bed noiseless by means of a cushion, upon which the springs are impinged when the bed is in use, and at the crossings of the iron straps, where they come in contact, and also in making the beds with rounded corners, so as to fit bedsteads of modern construction and avoid interference from corners of the posts projecting inward.

To enable others skilled in the art to make and use my invention, I will describe its construction and operation.

To make the cushion, I take paper, cloth, or other suitable material, and cut the same in pieces of proper size, which I wrap around the under strap of iron under each spring, and at each crossing, as shown in the accompanying drawing (marked A) by the colored spots, and secure the same in place with glue, paste, or other glutinous material, so that when the bed is in use the springs are impinged upon the cushion, which deadens the sound, and thus avoid the noise consequent upon the iron being

brought in contact, and the same effect is secured at the other crossings.

Another method is to cut the material for cushions of proper size and stitch the edges together, slipping them on the iron straps under the springs and at the crossings.

To construct the round corner, I take sheet-iron of proper thickness, and cut out the corners in quarter-circles, by punching or otherwise. I then punch a slot on each end of the corner, upon the same radius as the center, as shown in the accompanying drawing, (marked B,) by means of which, in putting the bed together, I am enabled to fasten the first and second straps, both length and cross wise, to each corner, with a single rivet at each end, and adjust the width and length of the bed so that the other straps are readily riveted in their places, and greater symmetry is given to the bed.

What I claim as my invention, and desire to secure by Letters Patent, is—

The application of the cushions to the metal strips at each intersection of the same, and the construction of the circular corner-pieces with slots, in the manner set forth, and for the purposes described.

J. FRANKLIN PECK.
